Primary Examiner — Karen S Acker*Assistant Examiner* — Wendy Arminio(74) *Attorney, Agent, or Firm* — Scully Scott Murphy and Presser(57) **CLAIM**

The ornamental design for a package for medical device, as shown and described.

DESCRIPTION

FIG. 1 is a perspective view of a package for medical device showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken lines depict features of the package for medical device that form no part of the claimed design.

1 Claim, 5 Drawing Sheets---
